UNITED STATES PATENT OFFICE.

ARTHUR WILLIAM WHISTLECROFT, OF LONDON, ENGLAND, ASSIGNOR TO RADIO CORPORATION OF AMERICA, A CORPORATION OF DELAWARE.

ELECTRIC CALLING DEVICE.

Application filed June 12, 1922, Serial No. 567,544, and in Great Britain June 13, 1921.

This invention relates to electric calling or alarm devices adapted to give an audible or visible call or alarm on the receipt of a predetermined number of impulses, for instance a predetermined number of wireless signals of a given duration.

Alarm apparatus constructed in accordance with the invention comprises means for preventing impulses shorter than the predetermined calling signals from affecting the rest of the mechanism and means for storing up the first of the calling signals until the required number has been received, whereupon the alarm is given, so that should the sequence of calling signals be interrupted, for instance, by jamming signals, the effect of these first signals may not be lost but that the alarm may be given so soon as the predetermined number of calling signals has been received.

Preferably means are also provided for preventing impulses longer than the given duration from affecting the storing mechanism.

My invention is illustrated by the accompanying drawings in which Fig. 1 is a side elevation of the apparatus involved in carrying out the invention herein described; Fig. 2 is a detail showing the clutch operating the contacts and associated mechanism; Fig. 3 is a detailed view of the safety magnet and associated parts.

A governor mechanism driven by any suitable source of power such as a clockwork motor may be constructed for example on the well known principle of an ordinary gramophone governor in which a driven spindle *b* carries two collars *c* and *d*, one of which *c* is fixed to the spindle and the other *d* is free to slide thereon and carries a friction disk *d*₁; the two collars are connected by flat springs *e* or pivoted double links carrying weights *f* either at the junction of the links or midway in the length of the springs. When the governor is revolved these weights tend to fly outward by centrifugal force, thus causing the free collar *d* to slide along the spindle.

Signals received by the wireless receiver are caused to actuate a relay, the secondary contacts of which close a circuit to energize an electromagnet *g*, hereinafter called the Morse magnet, which may be polarized if it is desired to have a more sensitive and quicker acting magnet. The armature *g*₁

of this magnet is attached to a spring influenced bar *h* pivoted near its middle. Normally the end of the bar remote from the armature rests on the friction plate *d*₁ so preventing the shaft *b* from running. On the receipt of a signal the Morse magnet *g* is energized and the end of the bar *h* leaves the plate *d*₁. The clockwork then commences to run. It will be understood that with ordinary Morse signals the lift of the bar *h* is so quick that the governor does not have time to run up to speed but just slips round slightly at each lift. The clockwork therefore is not quickly run down. On the arrival, however, of a calling signal, the duration of which should be considerably greater than that of any ordinary signal, the governor gains speed and the friction collar *d* rises. After the collar *d* has risen a short distance, say, for instance, in half a second,

a contact *j* is closed by an arm *ja* actuated by the collar. The contact closes a circuit to energize a second magnet *k* called the clutch magnet. A rotating wheel *l* (attached for example to one of the slow running spindles of the motor mechanism) has a soft iron rim *la*, see Figs. 1 and 2, and coaxial with this wheel is a soft iron spindle *m* free to move in centres. This spindle runs with clearance through the middle of the clutch magnet *k*. The spindle carries a pivoted or springy extension *m*₁ which is approximately at right angles to its axis and reaches out to the rim *la* but normally does not touch it. If the clutch magnet *k* is energized the spindle *m* and extension *m*₁ will be magnetized and be attracted to the now rotating rim *la* and revolve with it against the action of a returning spring *n*. The spindle *m* also carries another right angle extension *o* to act as a contact arm which, when it has travelled through a certain angle, makes contact with a flat spring *p* (see Figure 2). The time interval between the energizing of the Morse magnet *g* and the closing of this contact *o* *p* is the minimum length of the operating signal. This contact *o* *p* closes the circuit of a third magnet *q* (see Figure 1) called the cocking magnet.

Should the signal be over length the contact arm *o* will still carry on with the wheel *l* and close another contact *r* (Figure 2) to operate a fourth magnet *s* (Figure 1) called the tripping magnet, magnet *q* being all the while still energized. When the cock-

ing magnet q is energized a pawl t is pulled forward over a sector u cut with ratchet teeth. The sector u is not moved on this forward stroke, but will be moved one tooth if the pawl t is allowed to return to its normal position whilst engaging with the sector u . This will bring the final contact v which operates the alarm bell one step forward. The sector u is retained in this position by a detent w which is also under the control of an electromagnet x . The receipt of a second calling signal causes the sector to be moved another tooth and so on. If now, as aforementioned, the signal is over length and the tripping magnet s is energized, the pawl t is thrown out of engagement with the sector u and the cocking magnet armature and is allowed to return harmlessly to normal without registering a tooth. The same contact that operates the tripping magnet also energizes a fifth magnet y (see Figures 1 and 3) called the safety magnet which attracts an armature z and allows a bar za to rise and close a contact zb for a sixth magnet zc (Figure 1) which immediately energizes and brings a clamping stop zd down on to the friction plate d_1 instantly stopping the motor. This is to prevent signals of very long duration from making the clockwork run down. This contact remains made by a step on the bar za preventing the armature z from returning until the signal ceases, when the return of the bar h knocks the catch down by an arm ha and frees the stopping magnet. It will be understood that immediately the motor is stopped the clutch magnet k ceases to be energized and the contact arm o flies back to its stop o_1 (Figure 2). It is also readily understood that if the signal had been under length the cocking magnet q would not have energized as the contact bar o would not have reached the contact p . When the requisite number of correct length signals have been registered, in this case four, the contact v comes against contact v_1 (Figure 1) and starts an alarm signal. The same contact energizes the clearing magnet x which lifts the detent w from the sector u and allows it to be reset to zero under the action of a spring u_1 .

It will be seen that the effect of calling impulses is stored up irrespective of the intervals between their arrival so that if a distant station sends out a number of calling signals the alarm will be actuated so soon as the predetermined number has been received, even though there may have been, owing to jamming signals, gaps in the sequence.

This apparatus possesses the advantage that there are no parts in motion and no magnets except the magnet first receiving the impulse are energized when signals are not

coming in so that unnecessary wear is obviated.

Having described my invention what I claim is:

1. In a calling device adapted to be operated by a given number of signals of a given length, the combination of means for preventing signals shorter than a pre-determined length from affecting the said calling device, means for storing up the calling signals until the required number has been received, means for giving an alarm upon the receipt of the required number of calling signals, and means for preventing signals longer than the pre-determined length from affecting the storing mechanism.

2. In a calling device adapted to be operated by signals, the combination of a centrifugal governor, means for rotating it, a brake, means actuated by the receipt of a signal for releasing the brake, an electromagnet whose energizing circuit is controlled by the governor, and means for giving an alarm when said circuit has been completed for a given number of predetermined intervals of time.

3. In a call indicator, the combination of means responsive to signals, with a translating element arranged to be set into operation by received signals, a second translating element, means operated at a predetermined speed of said first named translating element to set said second translating element into operation, a pair of contacts and means controlled by said second translating element for causing relative step by step movement of said contacts to closed position.

4. In a call indicator, the combination of means responsive to signals, with a translating element arranged to be set into operation by received signals, a second translating element, means operated at a predetermined speed of said first named translating element to set said second translating element into operation, a pair of contacts arranged to be moved to closed position in a plurality of steps and means associated with said second translating element for causing relative step by step movement of said contacts.

5. In a call indicator, the combination of means responsive to signals, with a translating element arranged to be set into operation by received signals, a second translating element, means operated at a predetermined speed of said first named translating element to set said second translating element into operation, a pair of signal operating contacts and means for causing single step relative movement of said contacts toward closed position upon predetermined travel of said second translating element.

6. In a call indicator, the combination of

means responsive to signals, with a translating element arranged to be set into operation by said responsive means, a second translating element, means operated at a predetermined speed of said first named translating element to set said second translating element into operation, a pair of signal operating contacts, means for preparing for single step relative movement of said contacts toward closed position upon predetermined travel of said second translating element, and means operated upon predetermined additional travel of said second translating element to prevent such travel of said contacts.

7. In a call indicator, the combination of means responsive to signals, with a translating element arranged to be set into operation by received signals, a second translating element, means operated at a predetermined speed of said first named translating element to set said second translating element into operation, a pair of signal operating contacts, a pair of contacts and means controlled by said second translating element to cause relative step by step movement of said contacts toward closed position, and means responsive to duration of received impulses for positively preventing operation of said first translating element.

8. In a call indicator, the combination of

means responsive to signals, with a translating element arranged to be set into operation by received signals, a second translating element, means operated at a predetermined speed of said first named translating element to set said second translating element into operation, a pair of contacts arranged to be carried by relative step by step movement toward closed position, means for normally retaining said contacts in position, means operative in response to signals of predetermined duration for preparing such contacts for single step movement and means responsive to predetermined additional duration of received impulses for resetting said preparing means to initial position.

9. In a call selector, the combination of a pair of contacts arranged for relative step by step movement toward closed position, means for normally maintaining the space relation of said contacts, means for preparing said contacts for single step movement when the duration of received impulses exceeds a predetermined minimum value, and means for resetting said preparing means to initial position without actuation of said contacts when the duration of received impulses exceeds a predetermined maximum value.

ARTHUR WILLIAM WHISTLECROFT.
